UNITED STATES PATENT OFFICE.

CHARLES A. BULL, OF ALBION, NEBRASKA, ASSIGNOR TO THE B.-M. PRODUCTS COMPANY, INC., OF ALBION, NEBRASKA.

TIRE-CHAIN GUARD.

1,393,745.

Specification of Letters Patent. Patented Oct. 18, 1921.

Application filed August 23, 1920. Serial No. 405,428.

To all whom it may concern:

Be it known that I, CHARLES A. BULL, a citizen of the United States, residing at Albion, in the county of Boone and State of Nebraska, have invented certain new and useful Improvements in Tire-Chain Guards; and I do declare the following to be a full, clear, and exact description of the invention, such as will enable others skilled in the art to which it appertains to make and use the same.

This invention relates to tire-chain-guards, and more specifically to an improved fender construction including an improved attachment for preventing the tire-chain from engaging with the clamping device which holds the fender on the bracket that supports it.

One object of this invention is to provide an improved, yet very simple and cheap, device that can be quickly and easily attached in its effective position and will not rattle, come loose or slip from its effective position.

Other objects and advantages will be pointed out or implied in the following details of description, in connection with the accompanying drawings, in which:

Figure 1 is a side elevation of a portion of a fender, over a portion of a tire, my improved guard being applied thereto, and being shown in vertical section.

Fig. 2 is a bottom plan view of the improved guard and adjacent portions of the fender.

Fig. 3 is a sectional view along the line 3—3 of Fig. 2.

Fig. 4 is a perspective view illustrating the sheet metal portion of my improved guard.

Referring to these drawings in detail, in which similar reference characters correspond with similar parts throughout the several views, and in which the wheel W is indicated merely to show the relation of my improved guard thereto, the invention consists in the construction and arrangement of parts which will now be described as follows:

Referring more particularly to Figs. 2 and 3, it will be seen that the fender 1, its strut or supporting bracket 2, the supporting arm 3 and the eye-bolt 4 (which clamps the members 2 and 3 together) are of ordinary or previously known construction.

One of the essential features of this construction, in connection with the present invention, is the fact that the fender 1 is arched at its middle portion, while the strut or bracket 2 extends substantially horizontally from one side to the other of the fender, thereby providing a space between the arched under-surface of the fender and the horizontal upper surface of the bracket 2. The ends of the bracket 2 are rigidly secured to the edges of the fender 1, but the middle portion thereof is somewhat yieldable or springy, being formed of sheet metal. The serious difficulty encountered with a structure of this kind, is that the cross chains of the wheel chains are thrown by centrifugal force against the fender-supporting structure 2—3—4, and by continual hammering of this structure tends to and often succeeds in loosening the nut on the end of the bolt 4, so that the fender not only rattles, but is weakened because of insufficient supporting means. Moreover, the cross chains will sometimes catch and become broken or result in breaking the fender-supporting mechanism.

In order to obviate the above recited difficulties, I provide a guard such as illustrated at 5 and separately shown in Fig. 4. This guard includes the lower horizontal plate 6, an upright front plate 7 and an upright rear plate 8. These plates are apertured at 9 and 10, the aperture 10 being square or non-cylindrical so as to fit a non-cylindrical portion of the bolt 11 which extends through the apertures 9 and 10 and is provided with a nut 12 which has its upper edge or side approximately flush with the upper edge of the rear plate 7. This upper edge and that of the plate 8 are curved so as to conform to the under side of the arched fender; and when the bolt 11 is in place, it rests upon the upper side of the bracket 2 and presses the upper or free edges of the plates 7 and 8 firmly against this lower arched surface, the spring action of the bracket 2 assisting or co-acting with the bolt 11 for thus pressing the guard or shield 5 against the fender 1. The member 5 is trough-like, that is, has open ends which receive the supporting-structure 2—3—4 and these open ends are provided with upwardly and inwardly turned flanges or bracing ribs 13.

From the foregoing description, taken in

connection with Fig. 1, it will be seen that the bolt 11 is prevented from turning in consequence of its non-cylindrical portion fitting in the non-cylindrical portion of the plate 8, and that the nut 12 is prevented from accidentally turning in consequence of its engagement or close proximity with the lower surface of the fender 1. However, in attaching this device to the fender and its supporting-structure, a lever or wedge may be inserted between the members 1 and 2 for pressing them from one another, that is, for lowering the threaded end of the bolt so that the nut can be easily turned without resistance by the fender, and when the member 2 is released from the wedge or lever, its spring action will press the member 12 into the locked position shown in Fig. 1.

In effect, the plates 6, 7 and 8 merge with one another, being formed integrally of a single piece of sheet metal and the rear portion of this member 5 is gradually curved or convexed so as to eliminate any possibility of the tire-chain catching thereon, and at the same time, this curved or concaved portion 14 affords very great resistance against the hammering of the chains.

While this device is shown applied or attached to a previously known form of fender-supporting device, it is capable of being attached to any form of supporting de-

vice in which a space is provided under the arched fender for the bolt 11 to pass over the supporting device.

It is not intended to limit this invention to the exact details of construction and arrangement as described and illustrated, but changes may be made within the scope of the inventive ideas as implied and claimed.

I claim:

The combination with a wheel fender and a supporting device positioned beneath the fender and extending in spaced relation thereto, of a guard extending beneath the supporting device and having its side edge portions bent inwardly to provide flanges and its end portions carried upwardly to provide a bottom and end walls, the end walls engaging the underface of the wheel fender in front of and to the rear of the supporting device, and a securing bolt extending through the end walls of the guard and extending above and supported upon the supporting device and held against rotation, the bolt being provided with a nut at one end engaging the underface of the wheel fender and held against rotation thereby.

In testimony whereof I have hereunto set my hand.

CHARLES A. BULL.
